HYDRAULIC AND PNEUMATIC DRAIN AND
PIPE CLEANERGeorge M. Gould, Brooklyn, N. Y., assignor to
George E. Townsend, Brooklyn, N. Y.

Application April 11, 1935, Serial No. 15,921

7 Claims. (CL 221—77)

This invention relates to certain new and useful improvements in hydraulic and pneumatic drain and pipe cleaners.

- The primary object of the invention is to provide a hydraulic and pneumatic drain and pipe cleaner wherein a pressure tank for holding fluid and air under compression has a pneumatic pump device externally associated therewith for the forcing of air under pressure into the tank whereby fluid and air under pressure is discharged from the tank under control of an operator for causing fluid and air under pressure to flow through a water closet drain, pipe or the like for clearing the latter of obstructions.
- 15 A further object of the invention is to provide a combined hydraulic and pneumatic pipe cleaner that may be used as a hydraulic ram or as an air gun for the cleaning of pipes and the like.
- 20 A still further and important object of the invention is to provide a hydraulic and pneumatic drain and pipe cleaner wherein an air pump is externally associated with a fluid tank with all of the parts of the air pump readily accessible for repair or the like.
- 25 With the above and other objects in view that will become apparent as the nature of the invention is better understood, the same consists in the novel form, combination and arrangement of parts hereinafter more fully described, shown in the accompanying drawing and claimed.

In the drawing:—

- Figure 1 is a side elevational view, partly in section of a hydraulic and pneumatic drain and pipe cleaner constructed in accordance with the present invention, showing the lateral external positioning of the air pump relative to the fluid cylinder;

Figure 2 is a fragmentary side elevational view; and

- Figure 3 is a top plan view.

Referring more in detail to the accompanying drawing, there is illustrated a hydraulic and pneumatic drain and pipe cleaner comprising upper and lower headers 5 and 6 respectively with a fluid tank or cylinder 7 interposed between the headers 5 and 6 with the parts secured together in any convenient manner. A ring member 8 projects laterally of the upper header 5 in the plane thereof and is vertically aligned with a tubular casing 9 projecting laterally of the lower header 6, an air pump cylinder 10 having its lower end seated in the casing 9 while the upper end of the air pump cylinder 10 extends through the ring 8 for the reception of a closure cap 11 and carrying an upstanding tubular boss 12. Vent

openings 13 are formed in the air pump cylinder 10 above the supporting ring 8 and beneath the cap 11. The air pump cylinder 10 forms a closure for the upper end of the casing 9 and the lower end of said casing is closed by a removable drain plug 14 having threaded engagement therewith that permits access to the pump mechanism and other devices in the casing 9.

The pump mechanism includes a gasket type of piston 15 having wiping engagement with the 10 inner face of the air pump cylinder 10, the piston gasket 15 being secured to the lower end of the pump rod 16 that projects through the cap 11 and tubular boss 12 at the upper end of the pump cylinder with an operating handle or knob 17 on 15 the upper end thereof. A shock absorbing spring 18 is fixed to the piston rod 16 adjacent its lower end to limit and cushion upward movement of the piston 15.

As shown in Figure 1, a passageway 19 forms 20 communication between the casing 9 and the lower end of the fluid cylinder 7 and said casing 9 has a check valve 20 anchored therein above the passageway 19 and below the air pump piston 15, the check valve 20 opening in a downward 25 direction to permit the flow of air from the pump cylinder 10 under influence of the piston 15 into the fluid cylinder 7 and said check valve closing in an upward direction under influence of hydraulic and pneumatic pressure in the cylinder 7. 30 The interior of the casing 9 below the check valve 20 constitutes an air pocket 9a and the restricted passage 19 between the fluid cylinder 7 and pocket 9a permits compression of air in the pocket and excludes the admission of fluid to the 35 pocket. The check valve 20 is moved towards its seat by air pressure in the pocket and as stated, the air in the pocket is held under compression by hydraulic pressure in the fluid cylinder 7.

A valve casing 21 projects laterally of and depends from the lower header 6 diametrically opposite the casing 9 and is in communication with the fluid cylinder 7 by means of the passageway 22. A removable valve seat 23 is secured in the lower end of the valve casing 21 and is adapted 40 to be engaged by a valve 24 carried by the lower end of a valve rod 25, the valve 24 being normally retained on its seat 23 by means of the coil spring 26 surrounding the valve rod between the head of the valve casing and valve 24. The valve rod 25 has a liquid and air-tight bearing 27 in its passage through the upper end of the valve casing 21 and extending longitudinally of the fluid cylinder 7 passes through a bearing 28 carried by the upper header 5 diametrically opposite the 55

ring 8. A manipulating handle 29 for the device is carried by the upper header 5 and a lever or trigger 30 pivoted to the handle as at 31 has the upper end of the valve rod 25 pivotally attached thereto as at 32. It will therefore be seen from an inspection of Figure 1 that upon elevation of the free end of the trigger 30, the valve rod 25 is raised and the valve 24 removed from its seat 23.

Fittings of various types may be associated 10 with the lower end of the valve seat 23 and as shown in Figure 1, a pipe section 33 has threaded engagement at one end with the valve seat and a conical plunger device 34 is carried by the other end of the pipe section 33, this device being especially serviceable for cleaning toilet drains and the like. A pressure gage 35 is carried by the upper header 5 in communication with the fluid tank 7 and said header 5 has a filling opening 15 therein closed by the screw plug 36.

20 From the above detailed description of the invention, it is believed that the construction and operation thereof will at once be apparent, it being noted that operation of the air pump forces air into the fluid cylinder 7 and the discharge 25 of fluid and air under pressure when the cylinder 7 is controlled by the valve 24 operated by the lever or trigger 30. It will be understood that the device may operate solely as an air gun and to the exclusion of fluid. With the air pump device 30 located exteriorly of the fluid cylinder 7, access thereto may be readily had for repair purposes or the like, and this arrangement is also true of the control valve 24 for the discharge of fluid under pressure and air from the fluid cylinder 7.

While there is herein shown and described the preferred embodiment of the invention, it is nevertheless to be understood that minor changes may be made therein without departing from the 40 spirit and scope of the invention as claimed.

I claim:

1. In a device of the class described, a pair of 45 headers, a fluid cylinder and air pump cylinder with an air pump therein spaced from each other and anchored at their ends in the headers, a check valve arrangement controlling communication between corresponding ends of the cylinders and a manually operable valve arrangement supported on the two headers exteriorly of the fluid 50 cylinder to control the discharge from the fluid cylinder.

2. In a device of the class described, a pair of 55 headers, a fluid cylinder and air pump cylinder with an air pump therein spaced from each other and anchored at their ends in the headers, a check valve arrangement controlling communication between corresponding ends of the cylinders and a manually operable valve arrangement supported on the two headers exteriorly of the fluid 60 cylinder to control the discharge from the fluid cylinder including a valve rod, a handle carried by the upper header and a trigger pivoted on the handle and to which the valve rod is attached for operation of the valve rod and valve.

65 3. In a device of the character described, a pair of headers, a fluid cylinder and air pump cylinder with an air pump therein spaced from each other and anchored at their ends in the headers, a check valve arrangement controlling communication between corresponding ends of the cylinders, a manually operable valve arrangement 70

supported on the two headers exteriorly of the fluid cylinder to control the discharge from the fluid cylinder, including a tensioned valve rod slidable through the two headers, and an operating trigger for the valve rod at the upper end thereof.

4. In a device of the character described, a pair of 10 headers, a fluid cylinder and air pump cylinder with an air pump therein spaced from each other and anchored at their ends in the headers, a check valve arrangement controlling communication between corresponding ends of the cylinders, a manually operable valve arrangement supported on the two headers exteriorly of the fluid cylinder to control the discharge from the fluid cylinder, including a tensioned valve rod slidable through the two headers, an operating trigger for the valve rod at the upper end thereof, and a pressure gage for the fluid cylinder carried by the 15 upper header.

5. In a device of the class described, a pair of 20 headers, a fluid cylinder and an air pump cylinder with an air pump therein arranged in parallelism between the headers, the lower header having an air pocket at the lower end of the air pump 25 cylinder in communication with the fluid cylinder, a check valve in the pocket constructed and arranged to permit the flow of air from the air cylinder into the fluid cylinder and adapted to be closed by air pressure in the pocket under influence of hydraulic pressure in the fluid cylinder and a manually operable valve located exteriorly of the fluid cylinder to control the discharge from the fluid cylinder.

30 6. In a device of the class described, a pair of 35 headers, a fluid cylinder and an air pump cylinder with an air pump therein arranged in parallelism between the headers and anchored at their ends thereto, the lower header having a pocket 40 therein at the lower end of the air pump cylinder laterally of the fluid cylinder and in communication with the latter, a check valve in the pocket operative to permit the flow of air from the air pump cylinder into the fluid cylinder and closing in a direction to prevent the entrance of fluid into 45 the air pump cylinder, an outlet valve for the fluid cylinder carried by the lower header laterally of the fluid cylinder and a manually operable rod for the outlet valve exteriorly of the fluid 50 cylinder, and parallel therewith.

7. In a device of the class described, a pair of 55 headers, a fluid cylinder and an air pump cylinder with an air pump therein arranged in parallelism between the headers and anchored at their ends thereto, the lower header having a pocket 60 therein at the lower end of the air pump cylinder laterally of the fluid cylinder and in communication with the latter, a check valve in the pocket operative to permit the flow of air from the air pump cylinder into the fluid cylinder and closing 65 in a direction to prevent the entrance of fluid into the air pump cylinder, an outlet valve for the fluid cylinder carried by the lower header laterally of the fluid cylinder and a manually operable rod for the outlet valve exteriorly of the fluid 70 cylinder and parallel therewith, a handle carried by the upper header and a lever pivoted on the handle and pivoted to the upper end of the rod for the operation of the latter.

GEORGE M. GOULD.
